UNITED STATES PATENT OFFICE.

WILLIAM M. MITCHELL, OF LOUISVILLE, KENTUCKY, ASSIGNOR TO THE P & M COMPANY, OF CHICAGO, ILLINOIS, A CORPORATION OF ILLINOIS.

RAIL ANCHOR.

1,408,626.

Specification of Letters Patent.

Patented Mar. 7, 1922.

Application filed July 16, 1920. Serial No. 396,834.

To all whom it may concern:

Be it known that I, WILLIAM M. MITCHELL, a citizen of the United States, and a resident of Louisville, county of Jefferson, and State 5 of Kentucky, have invented certain new and useful Improvements in Rail Anchors, of which I do declare the following to be a full, clear, and exact description, reference being had to the following accompanying drawing, 10 forming a part of this specification.

My present invention, while adapted as to certain of its features, to other forms of rail anchors, is more particularly designed as an improvement upon the type of rail anchor 15 set forth in Letters Patent No. 1,338,148, granted to me April 27, 1920. The invention consists in the features of novelty hereinafter described, illustrated in the accompanying drawing and particularly pointed 20 out in the claims at the end of this specification.

Figure 1 is a view in vertical section through a railroad rail showing my improved anchor applied thereto, a portion of a rail- 25 way tie being shown in elevation. Figure 2 is a side view of my improved anchor. Figure 3 is a plan view of my improved anchor. Figure 4 is a view of a blank from which my improved anchor may be made. 30 Figure 5 is a detail view of the screw.

A designates the railway rail and B denotes one of the cross ties on which the rail is mounted. My present invention is shown as embodied in a one-piece form of rail anchor 35 very similar to that set forth in my above mentioned Letters Patent dated April 27, 1920. That is to say, the anchor comprises a jaw formed of an upper member c and a lower member c' an abutment plate c², and a 40 plate c² extending downwardly from the inner edge of the member c' of the jaw and at right angles to the jaw member c' and to the abutment member c².

Through the upper jaw member c is 45 formed a threaded hole adapted to receive a screw D, the upper end of which is suitably shaped to be engaged by a wrench. The lower end of the set screw D is preferably concave or cup-shaped as at d, there- 50 by giving to the peripheral portion of the lower end of the screw an annular cutting edge d' adapted to effectively indent or cut into the upper inclined surface a of the base flange a' of the rail A. While ad- 55 vantageous and preferable, it is not essen-

tial that the lower end of the screw D should be formed as shown in the drawing.

An important feature of my present invention is that the threaded hole in the upper jaw member c of the rail anchor extends 60 downwardly and outwardly from a vertical plane so that when the screw D is in position the upper end of the screw will similarly incline downwardly and outwardly from the web a² of the rail A. When the lower 65 end of the screw D is more or less recessed so as to form a peripheral cutting edge d', the forcing downward of the screw causes its lower edge portion d' to cut into or embed itself in the upper surface a of the rail base 70 flange and thus effectively hold the anchor against loosening or movement from off the rail. The downward and outward inclination of the screw D will be found advantageous, however, even when the end of the screw 75 D is formed blunt or with a point, although I regard the construction shown as preferable.

My improved anchor is preferably formed from plate metal sufficiently high in carbon as to give considerable resiliency thereto. Hence, when the anchor has been set upon the rail base flange and the screw D has been forced downward to engage the 80 upper face of the flange, the resiliency of the jaw member c of the anchor will tend at all times to hold the screw under compression against the base flange of the rail, so that notwithstanding the vibrations of the rail incident to the passage of traffic thereon, 85 there is a constant engagement of the lower end of the screw with the rail flange which aids in preventing the screw turning and working loose.

My improved anchor is preferably formed, 90 by means of suitable dies, from a blank such as shown in Fig. 4 of the drawings. Inasmuch as the most severe strain upon the anchor, incident to the tendency of the rail to creep, tends to spread the jaws c and c' of the anchor, I have provided that part c⁴ of the anchor that extends around the outer edge of the base flange with an offset rib c⁵, this rib being "bumped upward" by a suitable die in the process of forming the anchor. The reinforcing rib c⁵ preferably extends from about midway of the upper jaw c to a slight distance on the vertical plate c², as clearly shown in Fig. 1 of the drawing, as thereby great strength is given to the 110

anchor jaw at the point subjected to the greatest strain, while sufficient resiliency is allowed to the jaw to insure the constant compression of the lower end of the screw 5 D against the rail base flange when the anchor is in position for use.

In applying my anchor to a railway rail, the jaw portion of the anchor is forced over the base flange of the rail until the anchor is 10 in the position shown in Fig. 1 of the drawing, after which the screw D will be turned downwardly to cause its lower end to firmly engage the upper inclined surface of the rail base flange. As the screw D is thus 15 forced downward, its lower end embeds itself more or less in the upper surface of the rail base flange, and because of the downward and outward inclination of the screw, its 20 downward movement tends to draw the anchor up onto the rail, instead of tending to push it therefrom, as is the case when the screw is not thus inclined. The upper 25 resilient jaw c of the anchor yields slightly, as the screw is turned downward, and thus serves to hold the end of the screw D at all 30 times under compression against the rail base flange. As the rail A tends to "creep," the engagement of the abutment c² with the side of the tie B tends to produce a slight 35 rocking of the anchor, thereby causing the anchor jaws to firmly grip the base flange of the rail by what is commonly spoken of as a "shackle" action, thus serving to hold the rail against creeping, while the screw D not only aids in preventing any slipping 40 of the anchor longitudinally of the rail, but also also aids in resisting any tendency of the anchor to move laterally from engagement with the rail base flange.

I wish it understood that the details of construction above set out may be varied without departure from the spirit of the invention and that features of the invention may be employed without its adoption as an 45 entirety.

Having thus described my invention, what I claim as new and desire to secure by Letters Patent is:—

1. A rail-anchor comprising a jaw adapted 50 to engage one of the base flanges of a rail

and having an upwardly inclined upper member adapted to extend over the inclined upper surface of the base flange, and a set screw threaded through the upper jaw member at an acute angle thereto and adapted to force the jaw laterally into snug engagement with the rail base flange, substantially as described.

2. A rail anchor comprising a jaw adapted to engage one of the base flanges of a rail 60 and having an upwardly inclined upper member adapted to extend over the inclined upper surface of the base flange, and a set screw threaded through the upper jaw member at an acute angle thereto, said set screw having a peripheral cutting edge and adapted 65 to force the jaw laterally into snug engagement with the rail base flange.

3. A rail anchor comprising a jaw having 70 upper and lower members adapted to engage one only of the base flanges of the rail, a depending tie abutting portion, and a set screw threaded through the upper member of the jaw and adapted to engage the inclined upper surface of the rail base flange, 75 said set screw being inclined downwardly and outwardly and adapted to draw the jaw laterally into snug engagement with the base flange of the rail.

4. A rail anchor formed of resilient metal 80 and comprising a jaw having upper and lower members for engaging one of the base flanges of a rail, the portion of said jaw that extends around the edge of the base flange being formed with an offset strengthening rib, the end of which is spaced from the end of the upper jaw member, and a set screw threaded through the end portion of the upper jaw member and adapted to engage the upper face of the rail base flange. 90

5. A rail anchor comprising a jaw adapted 95 to engage one of the base flanges of the rail and having an upwardly and inwardly inclined, resilient upper member and a downwardly and outwardly inclined set screw threaded through the upper resilient member of said jaw and adapted to force the jaw laterally into snug engagement with the rail base flange.

WILLIAM M. MITCHELL.
